CLAIM

The ornamental design for a combined lid and container, as shown and described.

DESCRIPTION

FIG. 1 is a front, top, right perspective view of a combined lid and container showing my new design;

FIG. 2 is an exploded view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the Figures are for the purpose of illustrating portions of the combined lid and container and form no part of the claimed design.

1 Claim, 8 Drawing Sheets(56)
